UNITED STATES PATENT OFFICE

118,003

DESIGN FOR A TEXTILE FABRIC

Samuel E. Staines, Allendale, N. J.

Application March 17, 1939, Serial No. 83,645

Term of patent 3½ years

To all whom it may concern:

Be it known that I, Samuel E. Staines, a citizen of the United States, residing at Elmwood Avenue, Allendale, in the county of Bergen and State of New Jersey, have invented a new, original, and ornamental Design for Textile Fabrics, of which the following is a specification, reference being had to the accompanying drawing, forming part thereof.

The figure of the drawing is a plan view of a piece of textile fabric showing my design.

The repeatable unit of the design is shown within the rectangle marked upon the drawing, the sides of the rectangle not being exact boundaries of the design unit but each side thereof lying slightly outside the design unit.

I claim:

The ornamental design for textile fabric, as shown and described.

SAMUEL E. STAINES.
